UNITED STATES PATENT OFFICE.

STEVEN SCHWARTZ, OF CLEVELAND, OHIO, ASSIGNOR, BY MESNE ASSIGNMENTS, TO LOUIS F. SCHROEDER, OF CLEVELAND, OHIO.

FOUNTAIN-FAUCET.

1,127,683.

Specification of Letters Patent.

Patented Feb. 9, 1915.

Application filed January 26, 1912, Serial No. 673,650. Renewed July 3, 1914. Serial No. 843,945.

To all whom it may concern:

Be it known that I, STEVEN SCHWARTZ, a citizen of the United States, residing at Cleveland, in the county of Cuyahoga and 5 State of Ohio, have invented certain new and useful Improvements in Fountain-Faucets, of which the following is a specification.

My invention relates to improvements in 10 fountain or drinking faucets, and more particularly to improvements on my fountain faucet disclosed and claimed in my application filed January 23, 1911, Serial No. 604,040, the primary object of the invention 15 being to provide a generally improved sanitary drinking faucet of improved construction, particularly designed and adapted for use in lieu of the ordinary faucet whereby the necessity for the provision of a drinking 20 cup may be dispensed with.

A further object of the invention is to provide a combined fountain and filtering faucet having its fountain cup or spout rotatably mounted whereby the same is adapted 25 in its normal or depending position for use as an ordinary filtering faucet, and when it is desired to use the same as a drinking fountain, the rotatably mounted fountain cup may be turned to a reverse or upstanding 30 vertical position thus directing the discharging stream upwardly in fountain form.

A still further object is to provide an improved regulating valve for use in connection 35 with the fountain discharge port whereby the fountain stream issuing from the drinking fountain in its vertical position may be regulated in accordance with the varying water pressure in the source of 40 fountain supply.

With the above mentioned and other ends in view, the invention consists in the novel construction, arrangement, and combination of parts, hereinafter described, illustrated in 45 one of its embodiments in the accompanying drawings, and particularly pointed out in the appended claims.

Referring to the drawings forming a part 50 of this specification, Figure 1, is a side elevation of the improved faucet supply or valve head, the fountain cup or spout being shown in section for the purpose of clearer illustration of the parts. Fig. 2, a top plan view of the same. Fig. 3, a central longitudi-

dinal sectional view taken through the 55 fountain and filtering cups, the sleeve head being shown in front elevation. Fig. 4, a top plan view of the supply or valve head and the valved fountain discharge port, the sleeve head of the fountain cup being shown 60 in section.

Similar numerals of reference designate like parts throughout all the figures of the drawings.

The improved fountain or drinking faucet 65 comprises a valve stem or pipe 1, terminating in a supply or valve head 1^a, provided with oppositely disposed ports 2, and 3, the port 2, comprising the main discharge port for use when the improved faucet is used 70 as an ordinary filtering faucet in the position shown in the drawings, and the port 3, comprising the fountain discharge port adapted to communicate with the inlet port of the fountain cup when the latter is in its 75 vertical position for use as a fountain faucet. As a means for regulating the height and form of the fountain stream in accordance with the water pressure, said fountain discharge port is internally threaded 80 to receive and contain a threaded screw valve 4, said screw valve being longitudinally split by means of a central slit 4^a, adapted to form oppositely disposed communicating ports adapted to communicate with the inlet 85 port of the fountain cup in regulating the flow of water therethrough. As a means for adjusting the screw valve 4, and consequently regulating the size of the oppositely disposed communicating ports provided by 90 the slit 4^a, said screw valve 4, in the present instance, is provided with an ordinary screw head 4^b, adapted to operate in an enlarged or countersunk opening 3^a, of the fountain discharge port 3. 95

The fountain cup, proper, 5, has a reduced internally threaded portion 5^a, threaded upon an externally threaded portion of the cup stem 5^b, said cup stem terminating in a sleeve head 5^c, the latter being provided with 100 an inlet port 5^d, adapted to communicate with the respective ports 2 and 3, when the rotatably mounted cup is moved to its respective positions.

As a means for forming a proper connection or fit between the supply or valve head 1^a, and the sleeve head 5^c, the former is preferably tapered to fit within the corre-

spondingly flared bearing opening of the sleeve head, and as a means for adjusting and retaining said sleeve head 5^c, upon the tapered supply or valve head 1^a, the latter is provided with a thread stud 1^b, adapted to receive a washer 6, and an adjusting nut 7. The cup stem 5^b, is extended to form a strainer cup 8, extending into and spaced from the cylindrical walls of the fountain cup 5, and provided with an enlarged strainer chamber communicating with the inlet port 5^d, and provided with perforations or openings 8^a, in its cylindrical side walls. The strainer chamber 6, is adapted to receive and contain suitable strainer material 9, such as fine wire gauze as shown, or the like, and if desired, may be filled with suitable filtering material. As a means for removably retaining said filtering or straining material within the filtering or strainer chamber, the strainer cup is provided with a threaded thumb cap 10, threaded to the lower or outer end of the perforated strainer cup and above the central discharge opening 5^e, of the fountain cup.

As a convenience in operating the faucet in connection with the improved rotatably mounted fountain cup, the faucet spindle and handle 11, and bonnet portion 12, of the faucet body or pipe 1, are preferably arranged at one side thereof as shown instead of on top as usual in the ordinary commonly employed faucet.

From the foregoing description, taken in connection with the accompanying drawings, the operation and advantages of my invention will be readily understood.

Having thus described one of the embodiments of my invention, what I claim and desire to secure by Letters Patent is,—

1. A fountain faucet, comprising a supply head provided with oppositely disposed ports one of which is provided with a regulating valve, and a fountain cup rotatably mounted over said ports and regulating valve.

2. In a fountain faucet, a supply head having a main discharge port and a fountain discharge port, a regulating valve mounted in said fountain discharge port, and a fountain cup rotatably mounted on said supply head and covering said regulating valve.

3. In a fountain faucet, the combination with a supply head provided with a valved fountain discharge port; of a fountain cup rotatably mounted on said supply head and covering said valved fountain discharge port and adapted to be brought into and out of communication therewith.

4. In a fountain faucet, a supply pipe having a valve head provided with oppositely disposed ports one of which is threaded, a screw valve adjustably mounted in said threaded port, and a fountain cup having a flaring sleeve rotatably mounted on said valve head and having an inlet port adapted to be brought into and out of registry with said oppositely disposed ports of said valve head.

In testimony whereof I have affixed my signature in presence of two witnesses.

STEVEN SCHWARTZ.
